FUEL DISTRIBUTOR

Francis J. Wiegand, Ridgewood, N. J., assignor
to Wright Aeronautical Corporation, a corpora-
tion of New York

Application October 27, 1942, Serial No. 463,559

6 Claims. (CL. 261—90)

This invention relates to improved fuel distributing means for internal combustion engines equipped with a supercharger. An object of the invention is to provide an improved means for uniformly injecting the fuel into the intake air-stream of a supercharger impeller.

Specifically, the fuel is injected into the air-stream at the supercharger impeller intake through a plurality of small holes in an annular spinner member rotatable with the impeller and disposed adjacent the impeller intake. The fuel is fed into the spinner member and the rotation of this member imparts a rotational velocity to the fuel. A plurality of baffles are provided within this member to help rotate the fuel. As a result, the centrifugal force acting on the fuel injects the fuel into the airstream at the impeller intake through a plurality of small holes in the spinner. The baffles within the spinner are disposed so as not to form separate compartments but instead to bridge across the annular chamber within the spinner and leave a space between the baffles and outer circumference of this annular chamber. This disposition of the baffles permits equalization of the fuel level within the spinner, thereby providing for uniform discharge of the fuel through the holes in the spinner.

It has been found that engine performance can be improved by locating the constant pressure fuel discharge valve as close as possible to the point of discharge of the fuel into the impeller air-stream. This is probably due to boiling of the fuel in the passage between the discharge valve and the point of discharge of the fuel into the airstream since this portion of the fuel line is subjected to the low impeller intake pressure. Accordingly, it is a further object of this invention to provide a constant pressure discharge valve which is designed to be located as close as possible to the point of discharge of the fuel into the airstream.

Further objects of the invention will become apparent in reading the annexed detailed description in connection with the drawings, in which:

Fig. 1 is a diagrammatic side elevation of a radial cylinder aircraft engine with a portion of the supercharger housing broken away to broadly illustrate the invention;

Fig. 2 is an axial section through the supercharger and illustrating the impeller fuel injector;

Fig. 3 is an enlarged sectional view of a portion of Fig. 2;

Fig. 4 is an axial section through a modification;

Fig. 5 is an enlarged sectional view of a portion of Fig. 4;

Fig. 6 is a perspective view of one of the spinner baffles; and

Fig. 7 is a perspective view of the spinner member used in the modification of Figs. 4 and 5.

Referring to the drawings, a conventional radial cylinder aircraft engine is illustrated at 10 having a carburetor or other device 12 for proportioning the air and fuel. This carburetor may be similar to the pressure fuel-metering carburetor disclosed in Patent No. 2,165,447, issued July 11, 1939, to K. A. Browne, or any other conventional device for metering the fuel in proportion to the air flow may be used. Intake air passes from the carburetor to the intake of the supercharger impeller 14 through transversely extending passage or intake duct 16. Fuel is mixed with the air at the impeller intake in a manner herein-after described and the impeller raises the pressure of the combustible mixture to the diffusing chamber 18 from which the mixture is delivered to the various cylinders 20 through intake conduits 22.

The supercharger is provided with a front housing wall 23 and with a drive shaft 26. The drive shaft 26 extends through an opening in the rear wall 24 of the transversely disposed air intake duct 16. An oil seal sleeve 28 is carried by the impeller shaft 26 and is provided with seal rings 30 cooperating with a bushing member 32 secured to said rear wall 24 of the intake duct 16. A fuel passage 34, disposed within said rear wall 24, extends from the carburetor 12 to the bushing member 32. An annular passage 36 in the bushing 32 interconnects this fuel passage 34 with a passage 38 leading to a constant pressure discharge valve indicated generally at 40. This valve is supported on the rear wall of the supercharger housing and comprises a valve seat 42 and a movable valve member 44 biased to a closed position by a spring 46. A flexible diaphragm 48 is secured to the movable valve member 44 and divides the valve housing into chambers 50 and 52. Valve chamber 50 is subjected to the fuel pressure while chamber 52 is either vented to the atmosphere as at 54 or may be connected to the venturi suction of the carburetor in order to compensate for changes in fuel flow. Accordingly, the flexible diaphragm 48 operates to control the position of valve member 44 in response to variations in fuel pressure to maintain a substantially constant fuel pressure in the chamber

50, the compression stress in the spring 46 determining the magnitude of this pressure. Fuel is fed from the discharge valve 40 through passage 56 to a second annular passage 58 in the bushing 32. From this annular passage 58 the fuel flows through a plurality of holes 60 in the bushing 32 to the annular space 62 between the bushing and the impeller shaft. An annular spinner member 64 rotates with the impeller 14 and a seal ring 66 is provided between overlapping axial extensions 68 and 70 of the bushing and spinner respectively. From the annular space 62 the fuel flows to an annular chamber 72 in the spinner. The outer wall of this chamber is curved in an axial direction and a plurality of holes 74 extend through the spinner along the maximum circumference of the chamber 72. These holes communicate with the airstream just in front of the impeller 14. Also, a plurality of circumferentially disposed baffles 76 bridge the annular space 72 in the spinner in such a manner as to leave a clearance space between the outer edge of each baffle member and the outer wall of the annular chamber 72. Annular spacing members 78 and 80 between the spinner 64 and sleeve 28 maintain the spinner tightly against the hub of the impeller for rotation therewith.

In operation, rotation of the spinner member and its associated baffles 76 impart a rotational velocity to the fuel in the annular chamber 72 and as a result the centrifugal action on the fuel ejects the fuel through the plurality of holes 74. The clearance between each baffle and the outer wall of the annular chamber 72 permits the fuel level to equalize about this annular chamber. If, instead of bridging the annular chamber 72, these baffles formed solid barriers across the outer portion of the chamber, then the fuel level in the chamber might well be non-uniform thereby producing a non-uniform discharge of fuel through the holes 74. It is also important that the holes 74 be located at the outer diameter of the annular chamber 72 so that full advantage may be taken of the centrifugal force acting on the rotating fuel in the chamber 72. Furthermore, the discharge valve 40 should be located as close as possible to the spinner member 64, otherwise, boiling of the fuel may occur between the valve and the point of discharge of the fuel into the airstream with a resulting discontinuous fuel flow.

In the modification illustrated in Figs. 4 and 5, the general arrangement is similar to that illustrated in Figs. 1, 2 and 3 except that the constant pressure discharge valve has been designed to permit a much closer location of the valve to the spinner member. In this modification, a supercharger 100 is provided with a transversely extending air intake duct through the rear wall 102 of which an impeller drive shaft 104 extends. This rear wall 102 of the air intake duct is provided with a bushing member 105 which cooperates with an oil seal sleeve 106 having seal rings 108 carried by the impeller drive shaft 104 and cooperating with the bushing 105. A fuel passage 110 extends through the rear wall of the air intake duct from a suitable fuel metering carburetor or other device for metering the fuel in proportion to the air. An annular cap 112 is secured to the rear wall of the air intake duct about the bushing 105 to form a continuation 114 of the fuel passage 110 and to form an annular valve chamber 116 about the bushing member 105. An annular slide valve member 118 is slidably mounted on the bushing 105 and has one end extending into the valve chamber 116 for

cooperation with valve seat 120. The other end of the valve member 118 extends into an annular space 122 between the bushing 105 and the hub of the rear wall 102. An annular flexible diaphragm 124 has its inner end secured to the valve member 118 by suitable means, not shown, and has its outer end secured between the cap 112 and the wall 102. A spring 126 is disposed within the chamber 122 and biases the valve member toward its closed position against the fuel pressure on the other side of the diaphragm. The chamber 122 is vented to the atmosphere or is connected to the venturi suction in the carburetor through passage 128. The valve 118 is thereby operative to automatically maintain a substantially constant predetermined fuel pressure in the chamber 116. A packing ring 130 between the cap 112 and a shoulder on the bushing 105 provides an adequate seal for the chamber 116.

20 The valve 116 discharges the fuel into a plurality of passages 132 in the bushing which passages feed the fuel into the annular space 134 between the bushing 104 and the annular member 136. This annular member 136 is disposed between the oil seal sleeve 106 and a spinner member 138 to secure the spinner member against the hub of the impeller 100 for rotation therewith. In this modification the spinner member 138 overlaps the bushing member 105, and a seal ring 140 is provided between these members. The fuel is fed from the annular space 134 into the annular chamber 142 within the spinner, and the bridge type baffles 144 help impart a rotational velocity to the fuel to cause ejection of the fuel by centrifugal force through a plurality of holes 146 disposed along the maximum circumference of the annular chamber 142.

25 The spinner member with its baffles is essentially the same in both modifications. This spinner member is best seen in Fig. 7 which is a perspective view of the spinner illustrated in Figs. 4 and 5 while Fig. 6 is a perspective view of one of the baffles. However, it seems obvious that the baffles may be formed or cast integral with the spinner member.

30 In both modifications the fuel ejecting spinner member is adapted to discharge the fuel into the airstream at the intake of the impeller. A plurality of baffles are provided within the spinner to help impart a rotational velocity to the fuel and these baffles are disposed inwardly of the maximum circumference of the annular chamber within the spinner while the discharge holes are located along the maximum circumference. This 35 construction insures an even or symmetrical fuel level within the spinner so that a uniform fuel discharge is obtained. Also, in both modifications the constant pressure fuel discharge valve is located close to the spinner member so that a short fuel path is provided between this valve and the point of discharge from the spinner. This location of the discharge valve minimizes any boiling of the fuel as a result of the low pressure existing between the discharge valve and the point of discharge of the fuel into the airstream. Any such 40 boiling of the fuel tends to cause a discontinuous flow of fuel due to the presence of fuel vapor. Accordingly, it is seen that this invention provides for a more uniform mixture of air and fuel than heretofore attainable.

45 While I have described my invention in detail in its present preferred embodiment, it will be obvious to those skilled in the art, after understanding my invention, that various changes and modifications may be made therein without de-

parting from the spirit or scope thereof. I aim in the appended claims to cover all such modifications and changes.

I claim as my invention:

1. In an internal combustion engine, an annular supercharger impeller, an impeller drive shaft, said impeller having an annular intake opening about said drive shaft, an annular spinner member disposed about said impeller shaft adjacent said impeller, said spinner member providing an annular chamber about the impeller shaft, and a fuel pressure regulating valve automatically operable in response to the fuel pressure on its inlet side, said valve being disposed in close proximity to said spinner member for supplying fuel to said chamber, said spinner member having a plurality of openings through which fuel is discharged in front of said impeller.

2. In an internal combustion engine, an annular supercharger impeller, an impeller drive shaft, said impeller having an annular intake opening about said drive shaft, an impeller intake duct transversely disposed across the axis of said impeller, said drive shaft extending through a wall of said duct, an annular fuel chamber in said wall about said drive shaft, an annular spinner member disposed about the impeller shaft adjacent said impeller and arranged for rotation therewith, said spinner member providing an annular chamber about said impeller shaft, and an annular automatically operable fuel-pressure-regulating valve disposed about said impeller shaft for controlling the flow of fuel from said first mentioned chamber to said second mentioned chamber, said spinner member having a plurality of circumferentially spaced holes through which fuel is discharged from its annular chamber in front of the impeller.

3. In an internal combustion engine, an annu-

lar supercharger impeller, an impeller drive shaft, said impeller having an annular intake opening about said drive shaft, an impeller air intake duct transversely disposed across the axis of said

5 impeller, said drive shaft extending through a wall of said duct, an annular fuel chamber in said wall about said drive shaft, and an annular fuel pressure regulating valve disposed about said drive shaft and automatically operable to control the flow of fuel from said chamber into said air intake duct.

10 4. In an internal combustion engine, an annular supercharger impeller, an impeller drive shaft, and an annular fuel control valve concentrically disposed about said drive shaft, said valve being automatically responsive to the fuel inlet pressure thereto for controlling the discharge of fuel into the impeller airstream.

15 5. In an internal combustion engine, an annular supercharger impeller for the engine induction system, a fuel control valve concentrically disposed directly in front of said impeller, and means automatically operable in response to the fuel inlet pressure to said valve for regulating the 20 discharge of fuel therefrom and into the impeller airstream.

25 6. In an internal combustion engine, an annular supercharger impeller having an annular intake opening, a spinner member co-axially secured to said impeller for rotation therewith and 30 providing a fuel chamber in front of said impeller, and a fuel pressure regulating valve disposed in close proximity to said chamber and being automatically operable in response to the 35 fuel pressure on its inlet side for discharging fuel into said chamber, said member having a plurality of circumferentially spaced openings through which fuel is adapted to be discharged in front of said impeller from said chamber.

FRANCIS J. WIEGAND.
